(57) **CLAIM**

I claim the ornamental design for a cigarette-making machine, as shown and described.

DESCRIPTION

FIG. 1 is a perspective view of a cigarette-making machine. FIG. 2 is a front elevation view of the cigarette-making machine shown in FIG. 1.

FIG. 3 is a rear elevation view of the cigarette-making machine shown in FIG. 1.

FIG. 4 is a left elevation view of the cigarette-making machine shown in FIG. 1.

FIG. 5 is a right elevation view of the cigarette-making machine shown in FIG. 1.

FIG. 6 is a top plan view of the cigarette-making machine shown in FIG. 1; and,

FIG. 7 is a bottom plan view of the cigarette-making machine shown in FIG. 1.

The evenly spaced broken lines represent portions of the cigarette-making machine that form no part of the claimed design. The dot-dash-dot lines depict the bounds of the claim and form no part thereof.
